FUSE HOLDERS FOR ELECTRIC CIRCUITS
 Angelo Urani, St. Louis, Mo., assignor to McGraw-Edison
 Company, Elgin, Ill., a corporation of Delaware
 Filed Nov. 14, 1960, Ser. No. 69,184
 4 Claims. (Cl. 200—129)

This invention relates to improvements in protectors for electric circuits. More particularly, this invention relates to improvements in holders for electric fuses.

It is therefore an object of the present invention to provide an improved holder for electric fuses.

It is frequently desirable to mount a fuse holder in an opening in a panel; and it is oftentimes necessary to mount that fuse holder in that opening in such a way that the fuse holder will not "work loose" when the panel is subjected to excessive vibration. Lock washers are frequently used to try to keep the fuse holders from "working loose"; but lock washers are not always completely effective. Furthermore, lock washers are objectionable because they do occupy space and they do constitute finite weights. As a result, it would be desirable to provide a fuse holder which will not "work loose" if the panel is vibrated and which does not require a lock washer. The present invention provides such a fuse holder; and it is therefore an object of the present invention to provide a fuse holder which will not "work loose" if the panel is vibrated and which does not require a lock washer.

The present invention keeps the fuse holder from "working loose" by providing a resilient O-ring at the exterior of that fuse holder, and by causing that O-ring to engage the opening-defining portions of the panel. The resilient nature of the O-ring enables that O-ring to substantially absorb the vibrational forces which could tend to cause the fuse holder to "work loose"; and hence the fuse holder of the present invention will remain in tight engagement with the panel. It is, therefore, an object of the present invention to provide a resilient O-ring at the exterior of a fuse holder and to cause that O-ring to engage the opening-defining portions of a panel.

The O-ring at the exterior of the fuse holder of the present invention performs an additional function. Specifically, that O-ring coats with that fuse holder and with the opening-defining portions of the panel to provide a water-tight seal between that fuse holder and that panel. Such a water-tight seal is desirable; and it is attained in the present invention without the need of any extra parts.

The O-ring at the exterior of the fuse holder of the present invention performs still another function. Specifically, that O-ring serves as a positioning shoulder for the fuse holder. In doing so, that O-ring determines the extent to which the body portion of the fuse holder can be telescoped through an opening in a panel; and it also contacts with a nut or other inexpensive fastener to fixedly hold that body portion in position relative to that panel.

Furthermore, the O-ring at the exterior of the fuse holder of the present invention performs yet another function. Specifically, that O-ring engages both the body portion and the closure of that fuse holder to provide a liquid-tight seal between that body portion and that closure. As a result, the fuse holder of the present invention can fully protect a fuse against liquid and moisture.

The closure for the fuse holder of the present invention is dimensioned so the closed end thereof will be immediately adjacent the outer end of the fuse which is held by

2

that fuse holder. That fuse will have prongs which can be disposed within terminals of the fuse holder, and those terminals will tend to hold the fuse against dislodgment. However, if the fuse holder were to be subjected to excessive vibration, the prongs of the fuse might tend to "work" their way out of those terminals. Those prongs would, however, be wholly unable to "work" their way out of those terminals because the closed end of the closure for the fuse holder would be immediately adjacent, and would limit outward movement of the outer end of the fuse. As a result, the closure of the fuse holder of the present invention will make certain that full electrical contact is maintained between the prongs of the fuse and the terminals of the fuse holder.

15 The closure of the fuse holder of the present invention will, itself, be held against accidental separation from the body portion of that fuse holder by the engagement between the end face of that closure and the O-ring at the exterior of that fuse holder. The material of which that O-ring is made will have a high coefficient of friction; and hence that O-ring will resist accidental rotation of the closure relative to the body portion of the fuse holder.

Other and further objects and advantages of the present invention should become apparent from an examination 25 of the drawing and accompanying description.

In the drawing and accompanying description a preferred embodiment of the present invention is shown and described but it is to be understood that the drawing and accompanying description are for the purpose of illustration only and do not limit the invention and that the invention will be defined by the appended claims.

In the drawing,

FIG. 1 is a partially-broken, partially-sectioned side view of a fuse holder that is made in accordance with the principles and teachings of the present invention, and it shows the manner in which that fuse holder can be secured to a panel and it also shows the manner in which that fuse holder can hold a fuse.

40 FIG. 2 is a side elevational view of the body portion of the fuse holder of FIG. 1.

FIG. 3 is a view of the left-hand end of the body portion shown in FIG. 2,

FIG. 4 is a view of the right-hand end of the body portion shown in FIG. 2,

FIG. 5 is a side elevational view, on an enlarged scale, of one of the terminals that will be assembled with the body portion of FIG. 2,

FIG. 6 is an end view, on the scale of FIG. 5, of the right-hand end of the terminal in FIG. 5, and

50 FIG. 7 is a partially-broken, partially-sectioned side view of the closure for the fuse holder of the present invention.

Referring to the drawing in detail, the numeral 20 generally denotes the body portion of one form of fuse holder that is made in accordance with the principles and teachings of the present invention. That body portion is preferably made from a plastic material that is sturdy and tough. The body portion 20 is generally cylindrical, and it has a cylindrical recess 22 which extends inwardly from the right-hand end of that body portion. The axis of that recess is parallel to, but is spaced radially outwardly from, the geometric axis of the body portion 20. A passage 24 of semi-circular cross section extends inwardly from the left-hand end of the body portion 20; and the axis of that passage is coaxial with the axis of the cylind-

cylindrical recess 22. Further, the recess 22 and the passage 24 are contiguous.

The body portion 20 has a second cylindrical recess, and that second cylindrical recess is denoted by the numeral 26. Similarly, the body portion 20 has a second passage of semi-circular cross section, and that second passage is denoted by the numeral 28. The recess 26 and the passage 28 are contiguous, and their axes are coaxial. Those axes are parallel to the geometric axis of the body portion 20, and they are located on the same diameter of the body portion 20 on which the axes of the recess 22 and passage 24 are located.

The numeral 30 denotes a prismatic boss which is formed on the left-hand end of the body portion 20. That boss is disposed intermediate the outer ends of the passages 24 and 28; and it will serve as a barrier to any solder which might tend to flow from the region adjacent the outer end of the passage 24 to the region adjacent the outer end of the passage 28 during the time the fuse holder is being soldered into a circuit.

The numeral 32 denotes an annular groove at the exterior of the body portion 20, and that annular groove is closer to the right-hand end of that body portion than it is to the left-hand end of that body portion. A thread 34 is formed at the exterior of the body portion 20, and that thread extends forwardly from the annular groove 32. A thread 36 is formed at the exterior of the body portion 20, and that threads extends rearwardly from that annular groove. The direction, pitch and lead of the threads 34 and 36 are preferably the same.

The numeral 37 denotes a flat face which is provided at one side of the exterior of the body portion 20. That flat face can engage a flat part of the opening-defining portions of a panel; and it will coat with that part to prevent rotation of the body portion 20 relative to that panel.

The numeral 38 generally denotes a terminal which is a part of the fuse holder provided by the present invention. That terminal is preferably formed by rolling a strip of metal until the left-hand end 40 thereof has a semi-circular cross section and until the right-hand end 44 thereof has a circular cross section. That strip is initially wider at its right-hand end than it is at its left-hand end; and hence that right-hand end can form a substantially complete cylinder. An elongated slot 42 is formed in the left-hand end 40 of the terminal 38, and that slot facilitates the securement of wires or other conductors to that terminal. The circular right-hand end 44 is flared, as at 46, and it is slotted, as at 47. The flaring of that circular portion facilitates the introduction of the prong of a fuse into that circular portion, and the slotting of that circular portion enables that circular portion to resiliently grip that prong. The circular portion 44 of the terminal 38 is dimensioned to fit loosely within the recess 26 of the body portion 20, and the semi-circular portion 40 is dimensioned to fit snugly within the semi-circular passage 28 in that body portion. The circular portion 44 is dimensioned so the leading edge thereof is disposed a short distance inwardly of the right-hand face of the body portion 20. The left-hand portion 40 of the terminal 38 is dimensioned so it projects an appreciable distance outwardly beyond the left-hand face of the body portion 20.

The numeral 48 generally denotes the other terminal of the fuse holder. That terminal is identical in configuration to the terminal 38; but it is inverted so its left-hand, semi-circular end can fit in the passage 24 of semi-circular cross section in the body portion 20.

The numeral 50 denotes an O-ring which is made of rubber, synthetic rubber, elastomeric plastic, or the like. That O-ring will be readily yieldable, and it will have a high coefficient of friction. That O-ring can be extended to enable it to telescope over the threaded right-hand end of the body portion 20, and it will then retract to fit snugly within the annular recess 32 in that body portion. The O-ring 50 will be thick enough so it

will project outwardly beyond the opening-defining portions of a panel to which the fuse holder is secured.

The numeral 52 denotes a nut which has an internal thread that is complementary to the thread 36 on the body portion 20 of the fuse holder. That nut is preferably made of a plastic material that is sturdy and tough. The periphery of the nut 52 is knurled and it is also provided with two flat portions. The knurling facilitates finger-tightening of the nut, and the flat portions facilitate wrench-tightening of the nut. The nut 52 will be threaded onto the thread 36 of the body portion 20, and it will be tightened until its front face abuts the rear face of the panel to which the fuse holder is secured.

The numeral 54 generally denotes the closure for the fuse holder provided by the present invention. That closure has a generally frusto-conical configuration, and it has a closed right-hand end 56. An internal thread 58 is provided adjacent the left-hand end of the closure 54, and that thread is complementary to the thread 34 on the body portion 20 of the fuse holder. The left-end face 60 of the closure is dimensioned to engage the O-ring 50 whenever the closure 54 is disposed in assembled relation with the body portion 20 of the fuse holder.

The numeral 62 denotes a panel to which the fuse holder can be secured. That panel has a D-shaped opening 63 therein, and the flat side of that opening will receive and hold the flat face 37 on the body portion 20 of the fuse holder. The O-ring 50 will abut the front face of the panel 62; and that O-ring will respond to tightening of the nut 52 to yield and to deform into intimate engagement with the opening-defining portions of that panel. Such an intimate engagement is desirable because it will provide a liquid-tight seal between the body portion 20 and the panel 62. The yielding and deforming of the O-ring 50 is also desirable because it enables that O-ring to keep the fuse holder from "working loose" when the panel 62 is vibrated. It will be noted that the O-ring 50 serves as a shoulder for the body portion 20, and thus limits the extent to which that body portion can be telescoped through the D-shaped opening 63 in the panel 62.

The numeral 64 denotes a fuse of the type shown in Aldino J. Gaia application for protectors for electric circuits which was filed September 19, 1960, and which bears Serial No. 56,884 and which is owned by the assignee of this application. That fuse can be made quite small—having a length of approximately one-quarter of an inch and having a diameter of approximately one-quarter of an inch—and that fuse includes a wholly-enclosed fusible conductor. Two prongs, not shown, extend outwardly from the left-hand end of that fuse; and those prongs can be telescoped within and tightly held by the terminals 38 and 48 of the fuse holder.

Whenever the fuse 64 has the prongs thereof fully telescoped within the right-hand portions of the terminals 38 and 48, the right-hand end of that fuse will be immediately adjacent the inner face of the closed right-hand end 56 of the closure 54. This is desirable because that closed end of that closure will positively keep the prongs of the fuse 64 from "working" their way out of the terminals 38 and 48.

As the closure 54 is threaded onto the thread 34 of the body portion 20 of the fuse holder, the end face 60 of that closure will abut the right-hand face of the O-ring 50. The resulting engagement will be intimate, and it will provide a liquid-tight seal between the closure 54 and the body portion 20 of the fuse holder. In addition, that engagement will resist rotation of the closure 54 relative to that body portion. In this way, the rotation of the closure 54 into engagement with the O-ring 50 will provide the required sealing of that closure to the body portion 20 and will also prevent accidental separation of that closure from the body portion 20.

It will thus be seen that the O-ring 50 performs several

functions. For example, that O-ring serves as a shoulder for the body portion 20. Further, that O-ring provides a seal between that body portion and the panel 62. In addition, that O-ring keeps the fuse holder from "working loose" and thus eliminates the need of a lock washer. Also, that O-ring serves to provide a liquid-tight seal between the closure 54 and the body portion 20. Finally, the O-ring 50 provides resistance to the accidental separation of the closure 54 from the body portion 20.

The use of the present invention is not limited to holders for electric fuses. For example, the present invention could be used in making sockets for panel-mounted pilot lights, in making small, panel-mounted switches, in making sockets for transistors, in making sockets for vacuum tubes, and in making other panel-mounted devices. As a result, the present invention is very useful and very versatile.

Whereas the drawing and accompanying description have shown and described a preferred embodiment of the present invention, it should be apparent to those skilled in the art that various changes may be made in the form of the invention without affecting the scope thereof.

What I claim is:

1. In a panel-mounted holder for electric fuses, a cylindrical body portion that has one end thereof dimensioned to telescope through an opening in a panel and that has the other end thereof adapted to be disposed outwardly of said opening in said panel, an annular groove in the exterior of said portion intermediate said one and said other ends of said body portion, a screw thread on the exterior of said body portion that extends between said annular groove and said one end of said body portion, a second screw thread on the exterior of said body portion that extends between said annular groove and said other end of said body portion, an O-ring that has the inner periphery thereof disposed within and held by said annular groove, the outer periphery of said O-ring extending radially outwardly beyond the periphery of said one end of said body portion to engage the opening-defining portions of said panel, terminals that are disposed at least partially within said body portion and that are adapted to accommodate the prongs of an electric fuse, a closure removably mounted on said other end of said body portion, said closure having an internal thread engaging and being held by said second screw thread whenever said closure is in assembled relation with said body portion, said O-ring constituting a positioning shoulder for said body portion and for said closure and being adapted to serve as the sole positioning shoulder for said body portion and said closure, said O-ring being non-metallic and yieldable and deformable to form a water tight seal between said panel and said body portion, said O-ring being engageable by said closure to provide a water-tight seal between said body portion and said closure, and a fastener which engages the first said screw thread whenever said fuseholder is assembled with said panel and which coacts with said O-ring to hold said body portion in assembled relation with said panel, said second screw thread being adapted to releasably receive said internal thread and thereby releasably hold said closure in assembled relation with said body portion.

2. In a panel-mounted holder for electric fuses, a cylindrical body portion that has one end thereof dimensioned to telescope through an opening in a panel and that has the other end thereof adapted to be disposed outwardly of said opening in said panel, fuse-receiving terminals carried by said body portion, an annular groove in the exterior of said body portion intermediate said one and said other ends of said body portion, an O-ring that has the inner periphery thereof disposed within and held by said annular groove, the outer periphery of said O-ring extending radially outwardly beyond the periphery of said one end of said body portion to engage the opening-defining portions of said panel, a closure removably mounted on said other end of said body portion, said O-ring responding to stresses thereon to deform and form a water-

tight seal between said body portion and said opening-defining portions of said panel and to form a water-tight seal between said body portion and said closure, said O-ring constituting a positioning shoulder for said body portion and for said closure and being adapted to serve as the sole positioning shoulder for said body portion and said closure, said O-ring being adapted to substantially absorb vibrational forces tending to cause said body portion to "work loose" from said panel, a surface on said body portion intermediate said annular groove and said one end of said body portion that is adapted to receive a stiff fastener which can coact with said O-ring to hold said body portion in assembled relation with said panel, and a second surface on said body portion intermediate said annular groove and said other end of said body portion that releasably holds said closure in assembled relation with said body portion, whereby said body portion and said closure can engage each other and can interact with each other to confine an electric fuse, said O-ring being non-metallic and yieldable and deformable, said fastener engaging the first said surface on said body portion and holding the said O-ring in a stressed and deformed condition adjacent said opening in said panel whenever said device is mounted on a panel.

3. In a panel-mounting holder for electric fuses, a body portion that has one end thereof dimensioned to telescope through an opening in a panel and that has the other end thereof adapted to be disposed outwardly of said opening in said panel, fuse-receiving terminals carried by said body portion, an annular groove in the exterior of said body portion intermediate said one and said other ends of said body portion, a screw thread on that portion of the exterior of said body portion which is intermediate said annular recess and said one end of said body portion, and an O-ring disposed partially within and held by said annular groove, said O-ring being non-metallic and deformable, said O-ring extending outwardly beyond the periphery of said one end of said body portion to engage the opening-defining portions of said panel, said O-ring responding to stresses thereon to deform and form a water-tight seal between said body portion and said opening-defining portions of said panel, said O-ring constituting a positioning shoulder for said body portion and being adapted to serve as the sole positioning shoulder for said body portion, said screw thread being adapted to receive a stiff fastener which can coact with said O-ring to hold said body portion in assembled relation with said panel, said fastener engaging said screw thread on said body portion and holding said O-ring in stressed and deformed condition adjacent said opening in said panel whenever said device is mounted on a panel.

4. In a panel-mounted holder for electric fuses, a body portion that has one end thereof dimensioned to telescope through an opening in a panel and that has the other end thereof adapted to be disposed outwardly of said opening in said panel, fuse-receiving terminals carried by said body portion, a groove in the exterior of said body portion intermediate said one and said other end of said body portion, and a non-metallic and deformable resilient member disposed partially within and held by said groove, said resilient member extending outwardly beyond the periphery of said one end of said body portion to engage the opening-defining portions of said panel, said resilient member responding to stresses thereon to deform and form a water-tight seal between said body portion and said opening-defining portions of said panel, said resilient member constituting a positioning shoulder for said body portion and being adapted to serve as the sole positioning shoulder for said body portion, and a surface on said body portion intermediate said groove and said one end of said body portion that is adapted to receive a stiff fastener and which can hold said fastener at different distances from said groove, whereby said holder for electric fuses can be mounted on panels of different thicknesses, said fastener and said surface coacting with said resilient member to hold said body portion

in assembled relation with said panel, said fastener engaging said surface on said body portion and holding said resilient member in stressed and deformed condition adjacent said opening in said panel whenever said device is mounted on a panel.
